UNITED STATES PATENT OFFICE

THEODORE JOHNSON, OF ERIE, AND PAUL G. JOHNSON, OF WESLEYVILLE, PENNSYLVANIA, ASSIGNORS TO JOHNSON METAL PRODUCTS COMPANY, OF ERIE, PENNSYLVANIA, A CORPORATION OF PENNSYLVANIA

SCREEN FOR SWINGING WINDOWS

Application filed April 23, 1927. Serial No. 187,168.

Swinging windows, particularly those arranged on horizontal axes, have come into quite general use. Difficulty has been experienced with relation to such windows in providing a screen which would maintain a closure with the opening of the window. The present invention is designed to accomplish this purpose. Details and features of the invention will appear from the specification and 10 claims.

A preferred exemplification of the invention is illustrated in the accompanying drawings as follows:

Fig. 1 shows a front elevation of a window 15 with the screen in place.

Fig. 2 a section on the line 2—2 in Fig. 1.

Fig. 3 a sectional view of the bottom rail and closure strip of the upper screen on the line 3—3 in Fig. 2.

20 Fig. 4 an enlarged perspective view of the closure strip of the bottom screen.

Fig. 5 an enlarged perspective view of one of the stiles of the bottom screen, showing a means of attaching the screen.

25 1 marks the window frame, and 2 a sash mounted in the frame, this being usually formed of metal. A portion of the sash is open at 3 and a swinging sash 4 mounted in this opening. The swinging sash is mounted 30 on hinges 5 at each side of the sash and has a pivotal axis at 6. The upper rail of the swinging sash has a closure lip 7 and the lower rail a closure lip 8, the lip 7 being adapted to close on the inner face of the sash and the 35 outer lip on the outer face of the sash. The frame of the upper screen is placed against side stiles 9 of the main sash, the upper rail of the screen engaging a cap plate 10 arranged in the main sash and against which 40 the swinging sash closes.

45 Hooks 11 are secured to the inner faces of the side stiles of the upper screen, these hooks engaging the side stiles 9 of the main frame. A securing clip 12 having a bottom inwardly extending finger 13 and an upwardly extending finger 14 engages the hook 11, the rearwardly extending finger contacting a rib 17 in the edges of the opening in the main sash and the upwardly extending finger projecting 50 behind the hook 11 and engaging the upper

end of the hook so as to not only retain the screen against the stiles of the main frame but to support it vertically. A distance piece 15 is arranged back of the clip 12 and a screw 16 extends through the rib 17, distance piece 15, and into the clip 12.

55 In order to maintain a closure between the bottom rail of the screen and the swinging window as the window swings a closure piece 18 is provided. This is slidingly mounted on the bottom rail of the screen. It has an inwardly extending lip 19 which contacts the glass of the swinging sash. It has an inwardly extending flange 21 which extends over the top of the bottom rail. Bolts 22 extend 60 through the flange 21 and the lip 19 thus slidingly securing the piece 18 on the bottom rail. The bolts extend through plate springs 23, the plate springs yieldingly holding the closure pieces in their lower positions. When 65 the window is opened the glass in contact with the lip 19 swinging on the axis at 6 gradually rises and this lifts the closure piece while maintaining contact.

70 The lower screen closing the bottom of the opening in the main sash has a frame 24. This is seated against the inner edges 25 of the side stiles of the main sash 9. The clips 12 are pivotally secured by screws 27 on the side stiles 9 and are swung over the faces of the frames 24 so as to secure them against the side stiles. A closure piece 28 has downwardly extending ears 28^a overlapping the side stiles of the frame 24 which are secured by pivot pins 29 on the frames 24, the axis of the pivot pins coinciding with the axis 6 of the swinging sash. The closure piece 28 has notches 30 adapted to receive the window bars of the swinging sash and a downwardly extending lip 31 engaging the glass. An operating 75 clip 32 has an angle portion 33 secured to the plate 28. It has a bent portion 34 engaging one of the cross bars of the swinging sash and thus locks the plate 28 so as to swing with 80 the swinging sash.

85 An angle piece 35 extends across the bottom of the opening in the main sash and forms a face for the bottom rail of the lower screen. A clip 36 is secured to the angle plate 35 and engages the bottom rail, thus securing 90 95 100

the frame 24 against displacement vertically and the bottom of such frame from displacement inwardly from the window.

With this structure it will be seen that as the main window is swung the screens automatically maintain contact and closure.

What we claim as new is:—

1. The combination with a swinging window of a screen frame; and a closure piece 10 slidingly mounted on the lower rail of the frame adapted to maintain contact with a swinging window as it is swung.

2. The combination with a swinging window of a screen frame; and a closure piece 15 having a notched window bar receiving lip slidingly mounted on the bottom rail of the screen and adapted to maintain contact with a swinging window as it is swung.

3. The combination with a swinging window 20 of a screen frame; a movable closure piece secured to the bottom rail of the frame comprising an inwardly extending lip projecting below the rail, and an inwardly extending flange extending above the rail; and bolts extending through the flange, rail, and 25 lip slidingly securing the closure piece to the rail.

4. The combination with a swinging window 30 of a screen frame; a movable closure piece secured to the bottom rail of the frame comprising an inwardly extending lip projecting below the rail, and an inwardly extending flange extending above the rail; bolts extending through the flange, rail and 35 lip slidingly securing the closure piece to the rail; and springs between the lip and the rail adapted to yieldingly hold the closure piece in its lower position.

In testimony whereof we have hereunto 40 set our hands.

THEODORE JOHNSON.
PAUL G. JOHNSON.
